TYPEWRITING MACHINE

Anthony Utz, Hartford, Conn., assignor to Royal
Typewriter Company, Inc., New York, N. Y., a
corporation of New York

Application December 30, 1937, Serial No. 182,590

7 Claims. (Cl. 197—33)

This invention relates to new and useful improvements in typewriting machines generally, although more particularly to improvements in the means for adjusting the tensions of the type action springs and for indicating the amount of such adjustment, as shown in the patent to Myers, 1,983,482, Dec. 4, 1934. Reference is also made to the copending application of Lewis C. Myers, Serial No. 182,591, filed December 30, 1937.

In the Myers patent, a manually operable thrust screw is mounted in the rear of the machine frame for adjusting the anchor plate to which all of the type action springs are connected, and an indicator which is operable by the anchor plate is located for observation at the side of the machine frame. The full force of the type action springs is directed against the manually operable adjusting screw and consequently these springs offer considerable resistance to the thrust movement of the screw. Furthermore, by reason of the adjusting screw being located in rear of the machine, it is decidedly unhandy for the operator to effect an adjustment thereof and simultaneously observe the indicator which is at the side of the machine.

Among the several objects of the present invention are to provide a manually operable element in close proximity to the indicator whereby the operator may readily adjust the combined tension of the springs and simultaneously observe the effect of such adjustment; to provide means for counterbalancing the combined strength of the type action springs, and to provide a manually operable screw which is freely adjustable for varying the combined tension of said springs.

With these and other objects in view which will more fully appear, the nature of the invention will be more clearly understood by following the description, the appended claims, and the several views illustrated in the accompanying drawings.

In the drawings:

Figure 1 is a vertical section taken through a typewriting machine and showing the application of my invention,

Figure 2 is a horizontal section taken on the line 2—2 of Figure 1,

Figure 3 is an enlarged vertical section taken on the line 3—3 of Figure 2,

Figure 4 is a front elevation of the right hand base panel showing the indicator scale thereon,

Figure 5 is a horizontal section taken on the line 5—5 of Figure 1,

Figure 6 is a view showing the hand wheel and the upper end of the screw shaft in separated perspectives, and

Figure 7 is a perspective view of the indicator pointer.

Like reference numerals designate corresponding parts throughout the several figures of the drawings.

Referring to the accompanying drawings, I have illustrated my invention as being applied to a Royal standard typewriting machine, although it will be understood that the invention may be applied equally well to other known machines.

The typewriting machine includes a main frame A having a rear wall 5, and side walls 6 and 6a which substantially enclose and hide from view the working parts included within the main frame structure.

Located within the main frame is a plurality of type actions each of which includes a type bar 7 pivoted at 8 on a segment 9, a key lever 10 pivoted at 11 on a cross bar 12 which is secured to the side plates of the frame, a front link 13 which is pivoted at 14 to a cross bar 14a, a link 15 which is pivotally connected to the key lever 10 and to the link 13, an intermediate lever 16 which is pivoted at 17 to the cross bar 12, a link 18 pivotally connected to the front link 13 and the intermediate lever, and a link 19 which is pivotally connected to the intermediate lever 16 and to the heel of a type bar 7. A vertically disposed anchor plate 20 is journaled intermediate its upper and lower ends on horizontal pivots 21, 21 mounted in bearing lugs 22, 22 which are rigidly connected to and extend forwardly from the rear wall 5 of the main frame. The upper end of the anchor plate 20 is provided with a forwardly extending flange 23 having a plurality of openings 24, there being one opening for each type action spring. A universal bar 25 is mounted in the usual manner on the rear wall 5 of the frame and is connected by links 26 to the intermediate levers 16. A coil spring 27 is disposed around each link 26 and has its forward end connected thereto and its rear end engaged in the corresponding opening 24 of the anchor plate 20. Normally the springs 27 exert a rearward pull on the intermediate levers 16 to thereby normally retain the key levers 10 and the type bars in their rest positions.

The anchor plate 20 is adjustable to and fro of the machine in order to vary collectively the tensions of the springs 27 and thereby vary the touch of the type actions. For this purpose a bracket 28 is rigidly mounted on the cross bar 12 adjacent the right hand side wall 6 of the machine frame. This bracket includes spaced upper and lower plates 29 and 30 and journaled in these plates in a vertically disposed worm shaft 31.

having a manually operable element 32 such as a disc fixed to its upper end. The worm shaft 31 is threadably engaged with a worm wheel 33 fixed to a horizontal shaft 34 journaled in the bracket 28. Fixed to the inner end of the shaft 34 is an upwardly extending pointer arm 35 having its free end portion 36 disposed vertically above the disc 32, and inasmuch as the shaft 34 extends in a plane at right angles to the plane of the side wall 6, the upper end portion 36 of the pointer will be rocked in a plane parallel to said side wall. A link 37 has its front end pivotally connected to the pointer arm 35 and its rear end pivotally connected to a bracket arm 38 fixed to the upper end of the anchor plate 20. It will, therefore, be seen that when the disc 32 is rotated the pointer arm 35 will be rocked and the anchor plate 20 will be correspondingly rocked to thereby either increase or decrease the combined tension of the springs 27. By means of the worm shaft 31 and worm 33 very little effort will be required by the operator in effecting the desired adjustment of the springs 27.

The right hand side wall 6 of the main frame is provided with an elongated opening 39 and removably mounted in said opening is a closure plate 40 which is preferably formed of metal, although other material may be employed if desired. The plate 40 is provided with an opening 41 through which the disc 32 projects. The plate 40 is also provided with an arcuate opening 42 which is located above and in spaced relation to the opening 41, the opening 42 being preferably closed by a plate 43 of transparent material. Located on the outer face of the plate 40 directly above the opening 42 is a scale 44. The upper end 36 of the pointer arm is disposed directly in rear of the opening 42 and in cooperative relation to the scale 44. It will, therefore, be seen that the manually operable element 32 is disposed in close proximity to the indicating means so as to permit the operator to vary the combined tension of the springs 27 and simultaneously observe the effect of such adjustment.

Attached to the right hand bearing lug 22 is a forwardly extending arm 45 having a plurality of notches 46 at its forward end. A balance spring 47 has its rear end anchored to a lug 48 fixed to the lower portion of the anchor plate 20 and its forward end removably engaged with one of the notches 46. The tensile strength of the spring 47 is substantially equal to the combined tensile strength of all the springs 27, and consequently said spring 47 counterbalances the pull 55 of the springs 27 and insures greater ease in rotating the manually operable disc 32.

The pointer arm 35 adjacent its fulcrum is provided with spaced upper and lower stop shoulders 49, 50 adapted to respectively cooperate with a stop pin 51 fixed to the bracket 28 and thereby limit the rocking movement of the pointer arm and also limit the rotary movement of the disc 32.

It is of course to be understood that the details of structure and arrangement of parts may be variously changed and modified without departing from the spirit and scope of my invention.

I claim:

1. In a typewriting machine, the combination 70 with a main frame including a side wall having an opening, of a plurality of type actions supported within said frame, an anchor plate pivotally mounted within said frame, springs respectively connecting the type actions and the anchor 75 plate, a worm shaft rotatably mounted within the

main frame adjacent the opening in said side wall, a manually operable disc fixed to said shaft and projecting outwardly through said opening, a worm driven by said worm shaft, and operating connections between said worm and said anchor plate for rocking the latter to effect an adjustment of said springs upon rotation of said disc. 5

2. In a typewriting machine, the combination with a main frame including a side wall having spaced openings, of a plurality of type actions supported within said frame, an anchor plate pivotally mounted within the frame in rear of said type actions, springs respectively connecting the type actions and the anchor plate, a vertical 10 worm shaft rotatably mounted within the frame adjacent said side wall, a manually operable disc fixed to said shaft and projecting outwardly through one of said openings in said side wall, a worm driven by said shaft, an indicator pointer 15 rockable by said worm and disposed in rear of and viewable through the other opening in said side wall, and a link connection between said pointer and said plate.

3. In a typewriting machine, the combination with a main frame including a side wall having spaced openings, of a plurality of type actions supported within said frame, an anchor plate pivotally mounted within the frame in rear of said type actions, springs respectively connecting the type actions and the anchor plate, a vertical 20 worm shaft rotatably mounted within the frame adjacent said side wall, a manually operable disc fixed to said shaft and projecting outwardly through one of said openings in said side wall, a worm driven by said shaft, an indicator pointer 25 rockable by said worm and disposed in rear of and viewable through the other opening in said side wall, a link connection between said pointer and said plate, and stop means for limiting the rocking movements of said pointer. 30

4. In a typewriting machine, the combination with a main frame including a side wall having spaced openings, of a plurality of type actions supported within said frame, an anchor plate pivotally mounted within the frame in rear of said type actions, springs respectively connecting the type actions and the anchor plate, a worm shaft rotatably mounted within the frame adjacent said side wall, a manually operable disc fixed to said shaft and projecting outwardly through one of said openings in said side wall, a worm driven by said shaft, an indicator pointer 40 rockable by said worm and disposed in rear of and viewable through the other opening in said side wall, a link connection between said pointer and said plate, and stop means for limiting the rocking movements of said pointer. 45

5. In a typewriting machine, the combination with a main frame including a side wall having spaced openings, of a plurality of type actions supported within said frame, an anchor plate pivotally mounted within the frame in rear of said type actions, springs respectively connecting the type actions and the anchor plate, a worm shaft rotatably mounted within the frame adjacent 55 said side wall, a manually operable disc fixed to said shaft and projecting outwardly through one of said openings in said side wall, a worm driven by said shaft, an indicator pointer rockable by said worm and disposed in rear of and viewable 60 through the other opening in said side wall, a link connection between said pointer and said plate, and stop means for limiting the rocking movements of said pointer. 65

6. In a typewriting machine, the combination 70

with a main frame including a side wall having spaced openings, of a plurality of type actions supported within said frame, an anchor device pivotally mounted within the frame in rear of said type actions, springs respectively connecting the type actions and the anchor device, a worm shaft rotatably mounted within the frame adjacent said side wall, a manually operable member fixed to said shaft and projecting outwardly through one of said openings in said side wall, a worm driven by said shaft, an indicator device movable by said worm and disposed in rear of and viewable through the other opening in said side wall, and an operating connection between said indicator device and said anchor device.

7. In a typewriting machine, the combination with a main frame including a side wall having

spaced openings, of a plurality of type actions supported within said frame, an anchor device pivotally mounted within the frame in rear of said type actions, springs respectively connecting the type actions and the anchor device, a worm shaft rotatably mounted within the frame adjacent said side wall, a manually operable member fixed to said shaft and projecting outwardly through one of said openings in said side wall, a worm driven by said shaft, an indicator device movable by said worm and disposed in rear of and viewable through the other opening in said side wall, an operating connection between said indicator device and said anchor device, and stop means for limiting the rocking movements of said indicator device.
